UNITED STATES PATENT OFFICE.

EDWARD H. MIX, OF STAMFORD, CONNECTICUT, ASSIGNOR TO THE YALE & TOWNE MANUFACTURING COMPANY, OF SAME PLACE.

DESIGN FOR A PADLOCK-CASE.

SPECIFICATION forming part of Design No. 23,642, dated September 11, 1894.

Application filed July 31, 1894. Serial No. 519,119. Term of patent 7 years.

To all whom it may concern:

Be it known that I, EDWARD H. MIX, a citizen of the United States, and a resident of Stamford, in the county of Fairfield and State of Connecticut, have invented and produced a new and original Design for a Padlock-Case, of which the following is a specification, reference being had to the accompanying drawing, which represents a perspective view of a padlock showing my design.

The leading feature of my design consists in the case simulating, in shape, a trefoil, or a leaf having three cusps.

1 represents a case simulating, in shape, a

trefoil having rounded side portions 2 and 15 downward projection 3.

4 represents a circular shackle and 5 represents an opening between the body and the shackle.

Having thus described my invention, the 20 following is what I claim as new therein and desire to secure by design Letters Patent:

The design for a padlock case substantially as herein shown and described.
